UNITED STATES PATENT OFFICE.

HERBERT T. GUTHRIE, OF NEW YORK, N. Y.

AUTOMATIC AND SEMI-AUTOMATIC KEY-LEVER ACTUATOR.

1,206,534.

Specification of Letters Patent. Patented Nov. 28, 1916.

Application filed February 29, 1916. Serial No. 31,092.

To all whom it may concern:

Be it known that I, HERBERT T. GUTHRIE, a citizen of the United States, residing at 502 East Seventy-seventh street, New York, 5 borough of Manhattan, and State of New York, have invented certain new and useful Improvements in Automatic and Semi-Automatic Key-Lever Actuators, fully described and represented in the following 10 specification and the accompanying drawings, forming a part of the same.

The object of this invention is to provide means for applying power to secure automatic and semi-automatic operation of key-levers and other movable parts, and to use 15 essentially the same mechanism for both automatic and semi-automatic functions.

In using the parts which comprise the semi-automatic feature of the invention, a 20 manually started operation of the key-levers is completed by mechanism connected to the motive power which actuates the automatic mechanism.

The present invention is particularly de- 25 signed to be used in combination with typewriters, but it is not limited to such machines, and may be used with any other machine to which it may be adapted.

While recognizing that neither automatic 30 typewriters *per se* nor semi-automatic typewriters *per se* are new, I present herein novel automatic and semi-automatic devices, and particularly claim originality in the 35 idea of effecting automatic and semi-automatic operation in one machine. Moreover, I effect this novel automatic and semi-automatic operation by a simple and inexpensive construction in which the principal operative members economically perform a double 40 function, inasmuch as they are utilized both in the automatic and semi-automatic operation of the same machine.

My mechanism is adapted for combined 45 automatic and semi-automatic operation of typewriting machines, as shown in the accompanying drawing, and in this conjunction 50 will permit the same machine to be used either for automatic repetition of such matter as circular letters, &c., or for so-called "light-touch" operation in which the operator touches the typewriter keys lightly and the power-driven mechanism completes the stroke of the key-levers and their connected parts.

Power-driven automatic machines are

now well known in the art, such devices being usually constructed with an independent frame upon which a typewriter can be set and the key-levers connected by suitable rods with the automatic devices.

The advantages of using automatic machines for the repetition of typed matter are well recognized at the present time, but such automatic machines have not heretofore contained means for operating by "light-touch", and I am not aware of any "light-touch" machine which is now in use.

The labor saving and efficiency qualities of a power-driven light-touch typewriter are obvious, as an unskilled typist can produce as evenly printed matter as the most skilled operator; and in addition less energy is expended in operating such a typewriter, so that greater speed is attainable, and the operator does not tire so quickly as with an ordinary typewriter, and can therefore work more accurately.

The devices presented herein combine in one machine the advantageous automatic and semi-automatic features enumerated above, to produce which would heretofore have required two separate machines each costing about as much as the combination machines described herein.

The mechanism described below is adapted for automatically operating the key-levers of a typewriter under the control of a perforated selector-sheet, and is also adapted for use with a light-touch of the finger-keys, i. e., semi-automatically. In this mechanism, 85 the power-driven actuator which, in the automatic operation of the machine operates each key-lever under the control of the automatic selector, is also adapted to operate each key-lever under the control of the 90 finger-key by a partial depression of the same.

The invention may be embodied in diverse 100 mechanisms, several forms being shown in the annexed drawing. In all of these forms the connections to the key-levers of the machines to be operated are so arranged that when the finger-keys are partially depressed by hand, a rocker-lever which is also connected with the key-lever, is caused to engage the actuator, which then moves it to complete the movement of the key-lever. The use of such a connection permits a very 105 light touch on the part of the operator when operating the keys manually, and the key- 110

lever connection is normally detached from the actuator or else so constructed that it does not interfere with the automatic operation of the key-levers when desired. In 5 addition, a typewriting machine equipped with the combined automatic and semi-automatic mechanism may also be operated in the ordinary manual manner when desired.

10 The operation of these devices will be understood by reference to the annexed drawing, in which—

Figure 1 is a longitudinal vertical section of a combined automatic and semi-automatic 15 device provided with two grooved rolls for advancing two selector-sheets, by which the machine can automatically write circulars or letters under the control of one of the rolls and print inserts, such as different names 20 and addresses, upon the successive circulars under the control of the other roll. Fig. 1^a shows the use of a wedge to retract a pin from a grooved roll. Fig. 2 is a diagrammatic plan of the device shown in Fig. 1; 25 Fig. 3 is an enlarged view of the connection between the slides, the rocker-levers and actuator; and Fig. 4 shows one end of the actuator-head in front view, with several of the actuating dogs hinged thereon. Fig. 5 30 is a longitudinal vertical section of a combined automatic and semi-automatic mechanism operated by one grooved roll and selector-sheet; and Fig. 6 is an elevation of the same device viewed in the opposite direction, 35 showing means for adjusting the semi-automatic mechanism into and out of its operative position. Figs. 7, 8 and 9 are diagrams illustrating a modification of the connection between the key-lever and the rocker-lever 40 which is shown in Fig. 5, Fig. 7 being a side elevation of one of the rocker-levers and its connection to the key-lever; Fig. 8 an end elevation of the same parts; and Fig. 9 a plan of the same. Fig. 10 is an edge view of 45 the rocker-lever G and the link I shown in Fig. 1. Fig. 11 shows the rocker-lever engaged, and swung far enough by the actuator wholly to depress the key-lever connected with the rocker-lever; and Fig. 12 50 shows a cross-section of the lever g at the center of the connecting-rod i in Fig. 7.

In Figs. 1 and 2, a mechanism having two grooved rolls over each of which a perforated selector-sheet feeds, is provided with 55 independent rocker-levers adapted to engage a constantly moving actuator, each rocker-lever having a connection with a separate key-lever.

Slides are provided, with their ends adjacent to the rocker-levers and having sufficient lengthwise movement to cause the engagement of the rocker-lever with the actuator, each slide having a pin adapted to drop through the perforations in a selector-sheet

and to engage one or the other of the grooved 65 rolls and to be moved thereby, thus causing the slide to move lengthwise and tip the rocker-lever toward the actuator.

When tipped, the rocker-lever is engaged by the actuator upon its downward movement, and is thereupon moved sufficiently by the actuator to produce the entire movement required of the connected key-lever.

In Figs. 1 and 2, A designates one of the side-frames of the device, between which are 75 extended roll-shafts B, B', an eccentric-shaft C and a power-shaft D which is driven by any suitable means. The shafts B and B' rotate the grooved rolls E and E' continuously in the direction of the arrows, 80 such rolls carrying the perforated selector-sheets F and F', which are fed by them. The shaft D is connected by clutches S, S', with the roll-shafts B and B', and clutch-levers T, T' are shown to actuate the 85 clutches.

As only one of the rolls is used at a time, means controlled by each selector-sheet is, in practice, provided in connection with the clutch-levers T, T', to shift each roll into 90 and out of operation. This allows the rolls to be brought into operation alternately, as is required in printing a letter and automatically making inserts therein. Such means for automatically shifting the clutches 95 is not shown herein, as it is a common mechanical expedient and forms no part of the present invention.

A rocker-lever G is located under the forward end of each key-lever H' and connected thereto by a link I having a slip-joint with the rocker-lever, as indicated in Fig. 10. Each rocker-lever is made in the form of a plate fulcrumed upon a universal rod J, and has a notch G' in its lower edge in 105 which the rod I is hooked by a loop I', as shown in Figs. 10 and 11.

An actuator is mounted adjacent to the forward ends of the rocker-levers, being operated from the shaft D by an eccentric-shaft C which is connected by link and arm to a rock-shaft C' which carries the actuator. Shafts C and D are connected by shaft D³ and gears C⁴ and D⁴.

Arms C² extend from the rock-shaft to 115 carry a cross-head C³ extended transversely of the machine before all of the rocker-levers G and carrying a spring-dog c⁴ for each of said levers; which dogs actuate the rocker-levers when said levers are tipped toward 120 them. The spring-dogs c⁴ are pivoted upon the head C³ and held each in working position by a spring c⁵.

The forward corner of the rocker-lever G when tipped upon its fulcrum, traverses 125 the curved dotted line x of Fig. 3, and when the actuator oscillates upon its fulcrum C', its dogs traverse the curve x', so that a for-

ward tipping of the rocker-lever enables the dog to engage it.

The dogs c^4 oscillate constantly upon the curve w' , causing the dog, when said lever is tipped, to engage the upper front corner of the rocker-lever and carry it downward, as shown in Fig. 11, to complete the movement desired for the key-lever H' . The springs c^5 upon the dogs are provided to 10 permit their yielding if the rocker-lever G is tipped forward when the dog happens to be directly opposite it. As soon as the dog has cleared the rocker-lever after any collision of these parts, the spring c^5 forces the 15 dog back into operative position, enabling the dog to engage and depress the rocker-lever, as shown in Fig. 11, upon the next downward movement of the dog.

The rocker-levers, after each actuation, 20 are restored to their initial position by their connection to the key-lever which is in practice held normally raised.

The tipping of each rocker-lever is effected automatically by either of two slides 25 L or L' which are guided in combs M or M' , and abut at their forward ends against the edge of the rocker-lever G . Each slide is provided at its rear end with a vertically 30 movable pin e to coöperate with the grooved roll E or E' , and with a spring L^2 which tends to hold the slide in its rear position and retracts it after it has been moved forward.

The pins e normally rest upon the unperforated part of the selector-sheets F and F' which feed over the grooved rolls E and E' . When a perforation comes under one of the pins the pin drops through it into a groove in the associated roll, whereupon said pin 40 is moved forward by the roll and causes a lengthwise movement of slide L or L' which carries said pin.

The pin e may be formed with a shoulder which limits the distance the pin can drop, 45 and after it has entered the groove in the revolving roll the curved surface of the roll causes the withdrawal of the pin from the roll, after the pin has pushed the slide a sufficient distance to engage the rocker-lever with the actuator.

A positive means of retracting the pin from the groove in the roll is shown in Fig. 1 ^{2} , where the pin is provided with a head e' resting upon a wedge e^2 sustained upon the 55 comb M , the wedge operating during the forward movement of the slide to pull the pin positively out of the groove in the roll.

Which ever roll is in operation, the dropping of the pin through a perforation in 60 the selector-sheet into a groove of that roll causes the slide L or L' , carrying such pin, to be moved forward against the associated rocker-lever G and tip such rocker-lever into engagement with the actuator, thus caus-

ing the automatic depression of the connected key-lever.

The grooved roll, perforated selector-sheet and pins resting upon such sheet and adapted to engage with the roll through the perforations in the sheet and to be moved thereby, comprise a selector-mechanism by whose operation a rocker-lever G may be shifted into engagement with the actuator by diverse means within the scope of this invention.

The slides L and L' , or any longitudinally movable members, thus furnish transmitters to convey selective impulses from a plurality of selector mechanisms to a rocker-lever G in order to engage it with the actuator dog 80 c^4 and thereby produce the automatic depression of the key-lever H' .

The mechanism so far described is designed for operating the key-levers H' automatically, but I have combined with this 85 mechanism a very simple element which gives the typewriter a semi-automatic (or light-touch) operation: that is, a slight manual depression of the finger-keys serves to engage the rocker-levers with the actuator 90 and induce the remaining depression of the key-levers automatically. This is effected by a wedge N , shown in Figs. 1 and 3, which may be arranged to press upon a pin N' on either of the slides related to a single rocker- 95 lever, as the movement of either slide would tip such lever in the desired manner. The wedge is shown with a tapering lower end to push the slide toward the rocker-lever when the key-lever is slightly depressed, and 100 with a parallel body above such wedge-portion which, when the key-lever is further depressed by the actuator, moves smoothly by the side of the pin without producing any further movement thereof. The wedge is 105 shown touching the comb M' which prevents its moving backward. It is connected to the finger-lever by a rod r^2 so as to convey a slight movement of the finger-keys to the rocker-lever G . The wedge when moved, 110 operates to move the slide against the rocker-lever G and tip it, thus causing its engagement with the actuator, and permitting the use of the machine manually with a very light touch on the part of the operator. 115

When the wedge semi-automatic mechanism is in use, an imperforate portion of the selector-sheet is placed on the rolls under the pins, to prevent the pins from engaging with the rolls, and the rotation of the rolls is also 120 arrested.

The wedge for effecting a semi-automatic operation of the key-levers may obviously be used with the same effect in combination with other automatic mechanism than that 125 already described, and I have therefore in Fig. 7 shown it in a different device, which will be later described herein.

4 It is apparent that the device constructed with two rolls, as shown in Figs. 1 and 2, affords great advantage in the use of a typewriter, as it will automatically perform two different operations; the selector-sheet upon one roll when rotated governing the writing of a letter or circular, while a selector-sheet or perforated cards used in connection with the other roll, when rotated, will insert different addresses successively.

13 The sheet or perforated cards containing the addresses can be preserved for repeated use in circularizing or writing the same persons. Although these advantages attach to the use of two grooved rolls, a device embodying my invention is shown constructed with one grooved roll.

14 Figs. 5 and 6 show such a mechanism, adapted to operate both automatically and 20 semi-automatically with a single selector-sheet.

15 *a* designates one of the side-frames of this device between which are extended a roll-shaft *b*, an eccentric-shaft *c* and a rock-shaft 25 *d*. The shaft *b* rotates the grooved roll *b'* continuously, upon which the selector-sheet *b*² is fed. The shaft *c*² is driven by any suitable means and is connected by gearing *c*², *c*⁷ and *c*⁸ with the eccentric-shaft *c* and roll-shaft *b*, as shown in Fig. 6.

30 The rocker-levers *g* in this construction take the place of the slides and rocker-levers of the construction previously described, these rocker-levers *g* extending from the 35 grooved roll directly to a link or rod *i* depending from the key-lever, and such rod having a loose hook or detachable connection with the forward end of the rocker-lever *g*.

40 The rear end of the lever *g* extends over the grooved roll and has a pin *e* fitted movably in the lever so as to drop into the grooves of the roll when permitted.

45 The rocker-levers are constructed to rock or oscillate upon a fulcrum-rod *g*², which extends across the frame of the device, and each rocker-lever has a slot fitted movably to the fulcrum-rod so that the rocker-lever can make a sufficient forward movement to 50 engage an actuator constantly moving to and fro and adapted to tilt the rocker-levers.

55 The actuator consists of a head *d*² connected by arms *d*' with a rock-shaft *d*. An eccentric *c'* upon the shaft *e* moves the head *d*² to and fro as required. The head carries a series of spring-dogs *f* one for each of the rocker-levers or members *g*. Each of these rocker-levers has a notch *f*' adjacent to the spring-dog, and a shoulder *g*' at the rear end of such notch which normally clears the dog but is adapted to engage the same when the rocker-lever is moved slightly endwise in the direction of the arrow *x*² in Fig. 5.

60 85 Each dog is held in its operative position

by a spring *f*², such spring permitting the dog to yield if the lever *g* is moved endwise while the dog is raised into the notch *f*'; and such spring forcing the dog out again into its working position as soon as the dog is withdrawn from the notch, and thus enabling the dog to effect an immediate engagement with the rocker-lever, as shown in Fig. 6, upon the next upward movement of the dog.

75 78 In the automatic operation of this device the selector-sheet *b*² upon the grooved roll permits the selected pin to drop through a perforation into the grooves of the roll, which immediately pushes the 80 rocker-lever *g* forward or lengthwise sufficiently to engage the spring-dog *f*. Upon such engagement the dog or actuator pushes the rear end of the lever *g* upward, as shown in Fig. 6, which pulls the front end downward and depresses the connected key-lever 85 as required.

86 As shown in Fig. 12, the rod *i* has an upwardly bent hook at its lower end engaging a downwardly bent hook *j* upon the 90 front end of the rocker-lever *g*. This hooked connection of the link of the key-lever rod *i* forms a normally detachable connection from the key-lever to the rocker-lever, enabling a complete manual operation 95 of the finger-keys without interference from the lever *g* or the power mechanism. To effect semi-automatic operation with this device, levers *l* and *l'*, Figs. 5 and 6, are mounted over each of the rocker-levers *g* 100 to produce a manual movement of the pins *e*. The levers *l* and *l'* are pivoted upon universal rods *l*², which extend transversely of the machine and are attached to the frame. The levers *l* and *l'* are joined together at *l*², 105 and the forward end of the lever *l'* is, when the key-lever *i* is depressed, engaged by a spring latch *k* upon a rod *k*' joined to the key-lever at *k*². The rear end of the lever *l* is formed with a slot *m*, and the pin *e* is extended upward from the rocker-lever through the said slot and formed with a head to rest upon the lever *l* at the sides of the slot. A spring *n* is attached to a suitable extension from the frame and tends to hold the rear end of the lever *l'* lowered and the rear end of the lever *l* raised, which operates to hold the pins clear of the grooved roll when semi-automatic operation 110 is desired, the selector-sheet being then removed from the roll. A stop-bar *l*⁴ is extended below the lever-joints *l*², as shown in section in Fig. 5 and in dotted lines in Fig. 6, to limit the downward movement of such lever-joints.

115 125 A slight manual depression of the finger-key moves the front end of the lever *l'* downward by means of the latch *k*, thus permitting pin *e* to drop into a groove of the constantly revolving roll *b'*. This in- 130

stantly produces a forward movement of the connected rocker-lever *g*, which results in its actuation by the adjacent spring-dog *f* and the immediate movement of the rocker-lever to depress the key-lever *h'*. The slot *m* in the lever *l* is made sufficiently long to provide for the requisite forward movement of the pin during its engagement with the roll. The levers *l* and *l'* are placed far enough above the rocker-lever *g* to allow the required upward movement of the latter.

When any of the key-levers is pulled downwardly by the hook *j* upon the head of the rocker-lever, an interference of the latch *k* and the lever *l'* would result if provision were not made for the latch to clear the lever *l'* at such time. Such clearance is effected by extending the lower end of the rod *k'* through a guide-socket *k''* in the forward end of the lever *g*, which socket operates, when the lever *g* is pushed forward to engage with the spring-dog *f*, to move the latch *k* out of line with the lever *l'*, as shown in Fig. 6. This permits the rod *k'* and latch *k* to make a much greater movement downward (in completing the movement of the key-lever) than the lever *l* is constructed to make, as that lever is intended to drop the pin *e* only a fraction of an inch to enter the grooves in the roll *b'*. In the simultaneous return of the key-lever and rocker-lever *g* to their normal positions, (which is effected by the key-lever spring present in all typewriters), the rod *k'* rises with the key-lever, causing the spring-latch *k* to yield laterally in passing the end of the lever *l'*, thus placing it in position to reengage such lever whenever its connected finger-lever is depressed. The downward movement of the pin *e* to engage the roll *b'* is very slight, and a corresponding slight manual movement of the finger-key is all that is necessary to move the latch *k* sufficiently to produce such movement of the pin, the remaining movement of the finger-key being automatically produced without any effort on the part of the operator. This is the light-touch (or semi-automatic) operation of the device.

To adjust the device for wholly automatic operation, the rear ends of the levers *l* are held downward in order that the pins *e* may rest normally upon a selector-sheet, yet extend far enough above the levers *l* to be able to drop through perforations in the sheet into grooves in the roll, as shown in Fig. 5. Such adjustment of the levers *l* is effected by springs *o* carried by an adjustable holder *p*. One of the springs is applied to each of the levers *l*, and the holder *p* can be moved to press the springs toward or from the levers *l*, by a handle *p'*, a rod *q*, and suitable connections to an arm *q'* upon the holder. A stop *p''* is provided near the handle *p'* to secure the holder in either of its adjusted positions. (See Fig. 6.)

The springs *o* are made of sufficient strength wholly to overcome the action of the springs *n* and are thus able to hold the rear ends of the levers *l* downward, as shown in Fig. 5, when operating the device automatically. The pins then rest normally upon the selector-sheet, and the apparatus is adjusted for wholly automatic operation; when they are raised by levers, *l*, *l'* the automatic action is suspended. When the springs *o* are retracted the spring *n* draws the joint of the levers *l*, *l'* downward into contact with the seat *l''* below their joint, thus lifting the front end of the lever *l'* upward to the latch *k*. The parts are thus placed in position to be operated by the manual depression of the key-lever. The wedge may also be applied to the device having the single grooved roll, instead of the levers *l*, *l'*; to effect a semi-automatic use of such roll. To produce this effect, a wedge operated by a key-lever is arranged to push the rocker-lever *g* forward, the same as described for pushing the slide *L'* in Fig. 1. Such wedge is shown at *r* in Fig. 7, having a guide upon the comb *M'* and its sloping edge fitted against a pin *s* upon the head of the rocker-lever *g*. The effect of the wedge is to shift the rocker-lever *g* into engagement with the moving dog *f*, and thus secure the completion of the key-lever stroke as desired. When the wedge semi-automatic mechanism is in use, an imperforate portion of the selector-sheet is placed under the pins to prevent their engagement with the grooved roll and the rotation of the roll is also arrested.

It will be observed that the term "detachable connection" has been applied to the rod *i* or *l* by which the rocker-lever is connected to the key-lever; but the key-lever has another connection (of a less direct character) to the rocker-lever, consisting of the means to initiate the movement of the rocker-lever by a slight manual depression of the finger-keys. Such means is illustrated in the wedge as well as in the levers, and it will be readily seen that the wedge applied to the rocker-lever *g* in Fig. 7 performs the same function in manually engaging the rocker-lever with the actuator, as is effected by the levers *l*, *l'*, in their operation upon the pin *e*; and both of these mechanisms form auxiliary detachable connections between the key-levers and the rocker-lever, by which the key-levers can initiate the movement of the rocker-levers, but which connections are not themselves affected by the subsequent movement of the rocker-levers when engaged with the actuator; and either of such auxiliary connections may be used in conjunction with diverse automatic mechanisms.

In consequence of the practice of the Patent Office concerning the divisions of applications, parts of the mechanism above de-

scribed, which are believed to be novel and patentable, are not claimed specifically herein, but the right to claim those parts in another application is not waived.

5 Having thus set forth the nature of the invention what is claimed herein is:

1. A typewriter operator comprising key-levers, a power actuator therefor, operative connections adapted to be selectively interposed between said key-levers and actuator, means for automatically moving a selected connection into operative position, and means operable upon manual depression of a key-lever for moving a corresponding connection into operative position.

10 2. In mechanism for operating key-levers and other movable parts, the combination, with power-driven means for operating said levers and other parts, of means for automatically selecting said levers for operation by said power-driven means, and means actuated by manual selection of said key-levers for connecting manually selected key-levers with said power-driven means.

15 3. In a typewriter operator, the combination, with levers and other parts to be moved, of finger-keys operatively connected with said levers and other movable parts, a power-driven mechanism to operate said levers and other parts including a power-driven actuator and connections from the same to each key-lever including a rocker-lever, automatic mechanism for selectively engaging such connections with the power-driven actuator, and means for connecting the actuator through the rocker-levers with said levers upon manual depression of said finger keys.

20 4. In mechanism for operating key-levers and other movable parts, the combination, with a power-driven grooved roll and a selector sheet extended over the same, of rocker-levers having connections to the parts to be operated, an actuator for moving the rocker-levers when engaged therewith, a slide arranged to move lengthwise and tip the rocker-lever associated therewith, each slide having a pin adapted to engage the grooved roll to shift the slide lengthwise, springs to retract the said slides, and separate means for shifting the slide to connect the actuator through the rocker-levers with key-levers selected and manually depressed by the operator.

25 5. In mechanism for automatically operating key-levers and other movable parts, the combination, with a power driven selector mechanism comprising a power driven grooved roll, a perforated selector sheet, and pins resting upon the imperforate portion of such sheet and adapted to drop through the perforations in the sheet, to become engaged with and moved by the roll, of transmission members carrying said pins, rocker-levers arranged to be moved by the trans-

mission members, links connecting the rocker-levers to the parts to be operated, and a power driven actuator adapted to engage and operate the said rocker-levers when moved by the transmission members.

6. In mechanism for operating key-levers and other movable parts, the combination, with a power driven grooved roll and a selector sheet fed over the same, of mechanism for moving the parts to be operated, a slide for operating such mechanism and having a pin adapted to enter the grooves of the roll to actuate the said slide, and means for retracting the said pin from the grooves of the roll when the slide is thus shifted.

7. In mechanism for operating key-levers and other movable parts, the combination, with a power driven grooved roll and a selector sheet fed over the same, of rocker-levers having connections to the parts to be operated, an actuator for moving the rocker-levers when engaged therewith, and a slide arranged to move lengthwise and tip the rocker-lever associated therewith, each slide having a pin adapted to engage the grooved roll and shift the slide lengthwise, and springs arranged to retract the said slides.

8. In mechanism for operating key-levers and other movable parts, the combination, with two power driven grooved rolls and two selector sheets fed over the same, of mechanism for moving the parts to be operated, including rocker-levers, pairs of slides, one extending from each of said rolls to the same rocker-lever, each slide having a pin to engage a grooved roll and shift the slide lengthwise thereby tipping the rocker-lever, and a power-driven actuator to engage and operate the rocker-lever when it has been so tipped.

9. In a typewriter operator having key-levers held normally raised, the combination, with two power-driven grooved rolls and two selector sheets, of mechanism including a rocker-lever for moving each key-lever, two slides extended respectively from the said grooved rolls to the same rocker-lever each slide having a pin adapted to engage one of the grooved rolls, each of the pins when engaged with a roll operating to shift the associated slide lengthwise thereby tipping the rocker-lever, a power-driven actuator arranged to engage the rocker-lever when tipped, and the connection from the rocker-lever to the key-lever operating to retract the rocker-lever when thus tipped.

10. In mechanism for automatically operating key-levers, the combination, with a rocker-lever connected to each key-lever, and an actuator adapted to operate upon such rocker-levers, of two grooved rolls and selector-sheets located at different distances from the rocker-levers, a long slide extended from the farther roll to each of the rocker-levers, and a short slide extended from the

nearer roll to each of the said rocker-levers, the said short slides being supported movably between the longer slides and both slides for each rocker-lever being movable independently when engaged with their associated roll.

11. In mechanism for operating key-levers, the combination, with a grooved roll and selector sheet, of a power-driven actuator, a rocker-lever connected to each key-lever and adapted when tipped to engage and be moved by the said actuator, a slide with pin to engage the grooved roll and adapted to move lengthwise and tip the rocker-lever, and means connected to each key-lever adapted to initiate a power-driven movement of the key-lever when the latter is slightly depressed manually.

12. In mechanism for operating key-levers, the combination, with rocker-levers connected with the key-levers, of an actuator to move such rocker-levers, members movable lengthwise and operating when thus moved to engage the rocker-levers with the actuator, a grooved roll and pins each adapted to engage said roll and move a corresponding member lengthwise and produce an automatic actuation of the key-levers, and a wedge connected to move with the key-lever and operating to give a lengthwise movement to the said member and cause it to actuate the rocker-lever, thus effecting semi-automatic operation of the key-levers.

13. In mechanism for operating key-levers, the combination, with rocker-levers connected with the key-levers, of an actuator to move such rocker-levers, members movable lengthwise and operating when thus moved to engage the rocker-levers with the actuator, a grooved roll and pins each adapted to engage said roll and move a corresponding member lengthwise and produce an automatic actuation of the key-levers, and a wedge connected with each key-lever and operating upon its corresponding movable member to move the rocker-lever sufficiently to engage it with the actuator and thus produce a semi-automatic operation of the key-levers.

14. In mechanism for operating key-levers, the combination, with rocker-levers connected with the key-levers, of an actuator to move such rocker-levers, members movable lengthwise and operating when thus moved to engage the rocker-levers with the actuator, a grooved roll and pins each adapted to engage said roll and move a corresponding member lengthwise and produce an automatic actuation of the key-levers, and a wedge connected to move with the key-lever and operating to give a lengthwise movement to the said member and cause it to actuate the rocker-lever, thus effecting semi-automatic operation of the key-levers.

vers, the combination, with rocker-levers connected with the key-levers, of an actuator to move such rocker-levers, members movable lengthwise and operating when thus moved to engage the rocker-levers with the actuator, a grooved roll and pins each adapted to engage said roll and move a corresponding member lengthwise and produce an automatic actuation of the key-levers, and a wedge connected to move with the key-lever and operating to give a lengthwise movement to the said member and cause it to actuate the rocker-lever, thus effecting semi-automatic operation of the key-levers.

15. In mechanism for automatically operating key-levers and other movable parts, the combination, with a power-driven actuator, of a rocker-lever adapted to engage the same, power-driven selector mechanism comprising a grooved roll, a perforated selector sheet, and pins supported upon the imperforate portion of the selector-sheet and adapted to drop through the perforations therein to engage the roll, and transmission mechanism including a member confined to longitudinal movement and adapted to convey selective impulses from said selector mechanism to the rocker-lever and thereby shift said lever into the path of said actuator.

In testimony whereof I have hereunto set my hand.

HERBERT T. GUTHRIE.
